UNITED STATES PATENT OFFICE.

ABRAM C. MOTT, OF PHILADELPHIA, PENNSYLVANIA, ASSIGNOR TO THE
ABRAM COX STOVE COMPANY, OF SAME PLACE.

DESIGN FOR A HEATING-STOVE.

SPECIFICATION forming part of Design No. 16,654, dated April 20, 1886.

Application filed September 29, 1885. Serial No. 178,584. Term of patent 7 years.

To all whom it may concern:

Be it known that I, ABRAM C. MOTT, a citizen of the United States, residing in Philadelphia, Pennsylvania, have invented a certain 5 new and original Design for a Stove, of which the following is a specification.

My newly-invented design for a heating-stove is illustrated in the accompanying drawings, in which—

- 10 Figure 1 is a perspective view, and Fig. 2 is a sectional plan view on the line 1 2, Fig. 1. A represents the base of the stove, B the body, and D the cap, the base and cap projecting beyond the body, which is of vertical 15 rectangular form, with rounded corners b, the latter forming uninterrupted continuations of the sides, so that the main portion of the body is of the smooth outline illustrated in sectional plan view in Fig. 2. This body, although 20 smooth as to its main portion, is provided with a projecting ornamental door, F, and it may also have at its opposite sides projecting ornamental windows E. For practical reasons the body also has small horizontal ribs e.

I claim—

1. The herein-described design for heating-stove, the same comprising a projecting base, A, and cap D, and an intermediate body, B, of vertical rectangular form, with rounded corners b, the main portion of said body having 30 in sectional plan the smooth outline illustrated and described.

2. The herein-described design for stove, the same consisting of a base, A, and cap D, and a vertical rectangular body with rounded 35 corners, and having on the front a projecting door, F, and on the sides projecting windows E, as illustrated and set forth.

In testimony whereof I have signed my name to this specification in the presence of two subscribing witnesses. 40

ABRAM C. MOTT.
